UNITED STATES PATENT OFFICE

2,611,068

PIVOTALLY MOUNTED PLUG AND
VAPORIZER

William H. Wellens, Chicago, Ill.

Application April 12, 1946, Serial No. 661,848

6 Claims. (Cl. 219—19)

1

This invention relates to electrical devices in general and more particularly to electrically heated vaporizers of the type shown in my application, Serial No. 610,913, filed August 17, 1945, now abandoned, of which this application is a continuation in part.

In the aforementioned application, the vaporizer is provided with a pair of contact prongs adapted to be received in a wall socket for completing the electrical connections and for supporting the vaporizer. The contact prong, receiving openings of the wall socket are sometimes vertically arranged and sometimes horizontally arranged and accordingly the vaporizer of the aforementioned application may be used only in sockets having the socket openings horizontally arranged if the vaporizer is to be maintained vertical.

The principal object of this invention is to provide a vaporizer or other electrical device with means whereby it may be vertically mounted in a wall socket having plug contact prong openings either horizontally or vertically arranged. This may be accomplished by providing the electrical device with a pivotally mounted plug member carrying the contact prongs.

A further object of this invention is to provide improved means for establishing electrical connections between the device and the pivotally mounted plug member and for operating as a shut-off switch when the device is tilted from the vertical position.

Further objects of this invention reside in the details of construction of the improved vaporizer.

Other objects and advantages will become apparent to those skilled in the art upon reference to the accompanying specification, claims and drawing, in which:

Figure 1 is a rear perspective view of the vaporizer;

Fig. 2 is a vertical sectional view therethrough, taken substantially along the line 2—2 of Fig. 1;

Figure 3 is a sectional view taken substantially along the line 3—3 of Fig. 2.

Fig. 4 is a sectional view taken substantially along the line 4—4 of Fig. 3; and

Fig. 5 is a rear elevational view with a portion of the cover removed.

The vaporizer is generally designated at 10 and includes a base member 11, a plug member 12, and a cover member 13, all preferably made of plastic or other suitable insulating material. The base member 11 carries a heating element 14 below a tray 15 carrying vaporizable tablets 16 made of paradichlorobenzine, oil of cedar, or

2

the like. The electric heating element 14 heats the vaporizable tablets 16 to drive off vapors into the surrounding atmosphere.

The base member 11 is substantially box-like in configuration and includes side walls 18 and a bottom wall 19. The rear side wall 18 is provided with a cavity 20 for receiving the plug member 12, and the side wall adjacent the cavity 20 is provided with a hole 21 for the purpose of pivotally mounting the plug member 12. Also mounted in the side wall 18 adjacent the cavity 20 are electrical contacts 22, 23, 24 and 25 which are spaced circumferentially about the opening 21. The contacts 22 and 25 are secured to a contact strip 26 and the contacts 23 and 24 are secured to a contact strip 27. The contacts 22, 23, 24 and 25 are preferably in the form of rivets so that they and the strips are held in place on the side wall 18 of the base member 11. The contact strips 26 and 27 extend into slots 28 and 29 formed between projections in the base member 11.

The heating element 14 may include a ceramic form 31 carrying the heating element 32 and may also be provided with a pair of extensions 33 and 34 for providing electrical connections to the heating element and for physically supporting the same. The extensions 33 and 34 extend downwardly into the slots 28 and 29 and engage the contact strips 26 and 27. Screws 35 and 36, screw threaded through the side wall 18 of the base member, operate to clamp the extensions 33 and 34 to the contact strips 26 and 27, thereby completing electrical contact between them and also clamping the heating element 14 in place.

The tray 15 for supporting the vaporizable tablets 16 is preferably dish-shaped and is provided with a flange 38 to be supported on the top of the base member 11. The bottom of the dish member 15 is preferably provided with a slot 39 to provide circulation of air therethrough. The cover 13 is provided with an internal flange for holding the tray 15 in place on top of the base member and is also provided with openings 40 to permit the vapors to escape from the vaporizable tablets 16 into the surrounding atmosphere. In order to center the cover 13 on the base member 11, the upper portion of the cover is provided with protrusions 41 engaging the upper portion of the base member 11 and likewise the base member 11 is provided at its lower portion with protrusions 42, engaging the interior of the lower portion of the cover 13. In this way the cover is accurately centered on the base

member. The cover is also provided with a slotted opening 43 for the purpose of accommodating the plug member 12.

The plug member 12 carries a pair of contact prongs 44 and 45 which are adapted to be inserted in suitable openings in a wall socket. The contact prongs 44 and 45 extend through the plug member 12 and engage the contacts 22, 23, 24 and 25, carried by the base member. The plug member 12 is also provided with a stud 46 which extends through the opening 21 in the base member and a spring 47 interposed between a cotter pin 48 and the wall 18 urges the plug member 12 to the left as shown in Fig. 2. The spring 47, therefore, operates to insure good electrical contact between the contact prongs 44 and 45 and the contacts 22, 23, 24 and 25, and also at the same time, operates to frictionally hold the plug member 12 in rotative position with respect to the base member 11.

With the parts in the position shown in the drawing, the contact prongs 44 and 45 are horizontally arranged to fit into a wall socket having horizontally arranged contact prong receiving openings. The contact prong 44 engages the contact 25, and the contact prong 45 engages the contact 23, whereby a circuit through the heating element is completed from the contact prong 44 through contact 25, contact strip 26, extension 33, heating element 32, extension 34, contact strip 27 and contact 23 to contact prong 45.

If now the vaporizer is to be utilized with a wall socket having the contact prong receiving openings vertically arranged rather than horizontally arranged, then all that is necessary is to rotate the plug member 12 through substantially 90°. When this is done, the vaporizer is vertically mounted in the wall socket even though the socket openings are vertically arranged. The electrical connections to the heater element are then completed through the contacts 22 and 24 rather than through the contacts 23 and 25, as above. Universal application of the vaporizer to wall sockets having either vertically or horizontally arranged openings is, therefore, provided.

To shut off the vaporizer, the vaporizer may be removed from the wall socket or it may be tilted in either direction through substantially 45° and when the latter is done the contact prongs 44 and 45 become disengaged from the contacts 22, 23, 24 and 25, as illustrated in dotted lines in Fig. 5. The circuit connections to the electrical heating element 14 are, therefore, disconnected and the vaporizer turned off. In order to place the vaporizer in operation, all that is necessary then is to rotate it back to its vertical position.

While for purposes of illustration, one form of this invention has been disclosed, other forms thereof may become apparent to those skilled in the art upon reference to this disclosure and, therefore, this invention is to be limited only by the scope of the appended claims and prior art.

I claim as my invention:

1. An electrical device to be mounted vertically in a wall socket having a pair of vertically or horizontally arranged plug contact prong receiving openings comprising a base member of insulating material, a plug member of insulating material, a stud for pivotally mounting the plug member on the base member, a pair of contact prongs carried by the plug member on opposite

sides of the stud to be received and supported in the plug contact prong receiving openings, and electrical contacts circumferentially spaced from the stud carried by the base member in electrical engagement with the contact prongs when the contact prongs are vertically or horizontally positioned, and spring means acting between said stud and plug member for insuring good electrical contact between said contacts and said contact prongs and for frictionally maintaining the relative rotative positions of the plug and base members.

2. An electrical vaporizing device to be mounted vertically in a wall socket having a pair of vertically or horizontally arranged plug contact prong receiving openings comprising a base member of insulating material, a plug member of insulating material, a tray on said base for holding vaporizable material, a heating element below the tray, a stud for pivotally mounting the plug member on the base member, a pair of contact prongs carried by the plug member on opposite sides of the stud to be received and supported in the plug contact prong receiving openings, four electrical contacts carried by the base member and circumferentially spaced about the stud, two of the electrical contacts being in electrical engagement with the contact prongs when vertically positioned and the other two electrical contacts being in electrical engagement with the contact prongs when horizontally positioned, said electrical contacts being connected with said heating element.

3. An electrical vaporizing device to be mounted vertically in a wall socket having a pair of vertically or horizontally arranged plug contact prong receiving openings comprising a base member of insulating material, a tray on said base member for holding vaporizable material, a heating element below said tray, a plug member of insulating material, a stud for pivotally mounting the plug member on the base member for rotation about an axis generally parallel to the plane of said tray, a pair of contact prongs carried by the plug member on opposite sides of the stud to be received and supported in the plug contact prong receiving openings, four electrical contacts carried by the base member and circumferentially spaced about the stud, two of the electrical contacts being in electrical engagement with the contact prongs when vertically positioned and the other two electrical contacts being in electrical engagement with the contact prongs when horizontally positioned, and means for electrically connecting one of the first two contacts with one of the second two contacts and for electrically connecting the other contacts, said electrical contacts being electrically connected with said heating element.

4. An electrical vaporizing device to be mounted vertically in a wall socket having a pair of vertically or horizontally arranged plug contact prong receiving openings comprising a base member of insulating material, a tray adjacent the upper end of said base member for holding vaporizable material, a heating element below said tray, a plug member of insulating material, a stud for pivotally mounting the plug member on the base member for rotation about an axis generally parallel to the plane of the tray, a pair of contact prongs carried by the plug member on opposite sides of the stud to be received and supported in the plug contact prong receiving openings, a pair of vertically arranged contacts and a pair of horizontally arranged contacts car-

ried by the base member and connected with said heater, the contacts being circumferentially spaced from the stud, the vertically arranged contacts being in electrical engagement with the contact prongs when vertically positioned and the horizontally arranged contacts being in electrical engagement with the contact prongs when horizontally positioned, and means for electrically connecting one of the vertically arranged contacts with one of the horizontally arranged contacts and for electrically connecting the other vertically arranged contact with the other horizontally arranged contact.

5. An electrical device to be mounted vertically in a wall socket having a pair of vertically or horizontally arranged plug contact prong receiving openings comprising a base member of insulating material having a hole therein, a plug member of insulating material having a stud extending into the hole for pivotally mounting the plug member on the base member, a pair of contact prongs carried by the plug member on opposite sides of the stud to be received and supported in the plug contact prong receiving openings, electrical contacts circumferentially spaced from the stud carried by the base member in electrical engagement with the contact prongs when the contact prongs are vertically or horizontally positioned, and a spring between the stud and the base member for insuring good electrical engagement between the contacts and contact prongs and for frictionally maintaining the relative rotative positions of the base member and plug member.

6. An electrical device including a base member of insulating material, a tray for supporting vaporizable tablets, a pair of electrical contact strips carried by the base member, a heater element provided with a pair of extensions for sup-

porting the heater element under the tray and for electrically connecting the heater element to the contact strips, a pair of screws carried by the base member for forcibly engaging the extensions with the contact strips, a pair of contacts electrically connected to each strip, a plug member of insulating material pivotally mounted on the base member, and a pair of contact prongs carried by the plug member and adapted to be received in a wall socket, one of the contact prongs engaging one of the contacts of one contact strip and the other contact prong engaging one of the contacts of the other contact strip.
